UNITED STATES PATENT OFFICE.

HOWARD A. THAM AND THOMAS RALPH RIDLEY, OF AKRON, OHIO.

DESIGN FOR A BADGE OR SIMILAR ARTICLE.

Application filed April 16, 1925. Serial No. 13,141. Term of patent 14 years.

To all whom it may concern:

Be it known that we, HOWARD A. THAM and THOMAS RALPH RIDLEY, citizens of the United States, residing at Akron, in the county of Summit and State of Ohio, have invented a new, original, and ornamental Design for Badges or Similar Articles, of which the following is a specification, reference being had to the accompanying drawing, forming a part thereof, in which—

We claim:

The ornamental design for a badge or similar article as shown.

T. RALPH RIDLEY.
H. A. THAM.
